UNITED STATES PATENT OFFICE.

HERMON L. VAN VALKENBURG, OF NORWOOD, OHIO, ASSIGNOR, BY MESNE ASSIGNMENTS, TO ALLIS-CHALMERS MANUFACTURING COMPANY, A CORPORATION OF DELAWARE.

OIL-SWITCH.

1,127,119.

Specification of Letters Patent.

Patented Feb. 2, 1915.

Application filed August 21, 1905. Serial No. 275,125.

To all whom it may concern:

Be it known that I, HERMON L. VAN VALKENBURG, citizen of the United States, residing at Norwood, in the county of Hamilton and State of Ohio, have invented certain new and useful Improvements in Oil-Switches, of which the following is a full, clear, and exact specification.

My invention relates to switches for electric circuits and particularly to high voltage oil switches and of the vertically movable plunger type.

One of the objects of my invention is to provide a switch which is simple in construction and operation, compact and easy to assemble.

A further object is to provide a switch having a movable bridging contact formed of copper or brass laminæ which laminæ all bear with equal pressure on the stationary contacts, and leave the latter at the same time when the circuit is broken at said contacts.

A still further object is to provide improved connections between the line leads or conductors and the stationary contacts, which will permit said leads to be disconnected at will without the use of special tools.

My invention consists in the details of construction more fully described in the following specification and set forth in the appended claims.

In the accompanying drawings which illustrate my invention, Figure 1 is a sectional elevation of a switch embodying my invention, a part of a switch-board panel being shown in section; Fig. 2 is a plan view of the same; Fig. 3 is a rear elevation, the oil tank being in section and parts being broken away for the sake of clearness; Fig. 4 is a plan view of my preferred form of bridging contact; Fig. 5 is a side elevation of the same; Fig. 6 is a partial side elevation of a modified type of contacts, and Fig. 7 is an end view of the same.

I have shown at 1, a portion of a switch-board panel to the rear of which is connected by bolts 2 the cast metal bracket 3 which supports the switch and switch operating mechanism. The bracket 3 has a vertical portion by which it is securely held to the panel and a rearward horizontal extension 4 which supports the oil tank 5 and

which forms a cover for the tank and therefore one of the walls of the inclosure for the contacts. The tank is preferably suspended from the horizontal portion of the bracket by means of bolts 6 and thumb nuts, the bolts fitting into open slots 7 in the sides of the extension of the bracket and being pivoted to the lugs 8 which are riveted to the tank. Suitable handles 9, which are provided for convenience in moving the tank are also pivoted to the lugs 8.

The portion 4 of the bracket has at its lower side a comparatively narrow, long, integral lug 10. Securely bolted to the underside of this downwardly extending lug is the insulating supporting base 11 for the stationary contacts. This supporting base, clearly shown in Figs. 1 and 3 may be of any suitable insulating material, but I prefer to employ a soapstone slab. My manner of supporting this insulating base is an important feature of my invention. I prefer to employ for supporting the base only two bolts 12, which, as will be apparent from the drawings, are arranged exactly on the center line of the horizontal extension 4 of the bracket and in a line with the switch handle, hereinafter described. The bolts 12 are not flush with the top of the bracket, but pass through two holes located at the bottom of a central depression 13, shown in Fig. 1 and Fig. 2. This arrangement and number of bolts possess the following advantages over the use of four or more. The narrow bearing surface between the base and supporting bracket permits the two members to be easily, accurately, and closely fitted; less workmanship is required to prepare the parts, since less holes need be drilled; the tension of the two bolts which are in line and in the center of the slab will lessen the danger of cracking the latter and lastly a much narrower slab is required, and hence a more compact switch results.

Suitably located on the underside of the soapstone base are the stationary contacts 14. I have here illustrated a three-pole, double-break switch, and therefore six such contacts are required, this switch being adapted for a three-phase circuit. My invention is not limited however to a switch of any specific number of poles. These contacts 14 are secured to the lower ends of contact ter-

5 minal bolts or rods 15 and are prevented from turning by dowel pins, one of which is shown in Fig. 3 at 16. These contact terminals extend upward through suitable holes drilled in the soapstone base and out through the extension of the supporting bracket. I attach considerable importance to my method of connecting these contact terminals to the line conductors, and of insulating the same. The contact terminals 10 15 extend slightly above the bracket extension 4 and are threaded with a right hand standard thread. Connected to the ends of the line leads or conductors are brass or copper terminal members 17, which are threaded with a left hand thread and have at their lower ends an unthreaded nipple or extension of less diameter than the threaded portion. A connecting sleeve or collar 18 20 provided with a left hand thread at one end and a right hand thread at the other connects each threaded lead terminal with a contact terminal rod or bolt. By simply turning the sleeve until the nipple of the lead terminal comes into contact with the upwardly extending threaded contact terminal bolt, the two portions will be held firmly together. Over this connection is slipped 25 an insulating sleeve or tube 19, preferably of porcelain which rests on the insulating washer 20. This sleeve rests loosely on the washer and can be slipped upward at will to expose the connection. The advantage of this last explained construction is 30 apparent. When it is desired to disconnect the main leads, all that is necessary is to slip upward the sleeve 19 and turn the connecting collar 18. Thus no special tool is required, as is necessary when fixed porcelain tubes or bushings are employed.

40 The movable bridging contacts, the preferred type of which is shown in Figs. 1, 3, 4, and 5, at 21 are carried by a bar of insulating material 22 preferably of wood. Three contacts are shown in Fig. 1, one for 45 each pair of stationary contacts. Each bridging contact is composed of a number of laminae of good conducting material which are supported on the bar 22, and are secured thereto by means of a clamping bolt 21^a which passes through the supporting bar and through the laminae midway between their ends. These laminae, which are 50 somewhat U- or channel shaped, include arms 55 which extend outwardly different distances from the supporting bar and from the clamping bolt, the lever arms of the laminae being successively longer from the uppermost lamina to the lowermost lamina, and have their ends bent outwardly at right 60 angles to the arms, the extreme ends of the outwardly bent portions forming contact faces which are also located at different distances from the support and are in a horizontal plane at right angles to the clamping 65

7 ing bolt, which, as stated before, passes through the laminae midway between their ends. In order that all the laminae may bear with equal pressure on the contacts and all leave the latter simultaneously when the 8 circuit is broken, I provide all the laminae with equal effective free lever arms, and this I accomplish by arranging between the laminae, separating plates 21^b which are of increasing lengths from the uppermost plate to the lowermost plate.

9 Auxiliary brushes or arcing tips are shown at 24. The supporting bar 22 is connected at the ends with vertically movable bolts or rods 25, which are guided in open slots 26 in end lugs 27 of the supporting bracket extension, as is shown in Figs. 1 and 3, and extend beyond the oil tank through holes in the bracket. These rods are connected to the extremities of a triangular frame 28 10 hereinafter referred to.

11 My improvements in the construction of laminated contacts described above is not confined to movable bridging contacts, but may be applied to stationary contacts. In 12 Figs. 6 and 7 I have shown a portion of a switch having a solid bridging contact and laminated stationary contacts constructed in accordance with my invention. The stationary contacts 29 are composed of laminae 30 having equal lever arms, that is, the distances from the point of contact of each lamina 30 with the movable bridging contact 31, to its point of support is the same. As 13 is shown in Fig. 7, the bridging contact is V or wedge shaped, and the faces of the laminae are similarly arranged. In this type of switch a greater pressure can be obtained between the contact faces without increasing the force required to operate the switch.

14 The operating mechanism for the switch will now be described. The operating handle 32 extends through the switchboard panel so as to be in reach of the operator standing in front of the switchboard. This handle is pivoted to the supporting bracket 15 at 33 and has connected on the rear of the board an arm 34, which forms with the handle a bell crank lever. This arm 34 is pivoted to a link 35 which link and arm 16 constitute a toggle joint for forcing the contacts firmly together. The link is pivoted to the arm 36 at 37 which in turn is pivoted at its forward end at 38 to the stationary bracket 3, and at its rear end at 39 to the triangular shaped frame 28 heretofore referred to. The switch handle has a finger 40 which is adapted to contact with the lug 41 on the bracket to limit the downward movement of the handle. It is seen 17 that the operating mechanism is simple and effective. When the switch is in its closed position the contacts are locked firmly together by the toggle, the arms of which will be slightly off center. All that is necessary 18

in opening the switch is to move the toggle arms over the center when the contacts will be quickly separated by gravity.

Having thus described my invention, what

5 I claim as new and desire to secure by Letters Patent is:—

1. In a high-potential switch, a supporting bracket, an oil tank secured to the lower face of the bracket, a lug on the lower face 10 of the central part of the bracket, a depression in the upper face of said bracket, an insulating slab attached to the lower face of the lug, by a plurality of bolts in said depression and on a line with the center of 15 the switch supporting bracket, and contacts on said slab.

2. In a high-potential switch, a supporting bracket, an oil tank secured thereto, a central lug on the lower face of said bracket 20 extending substantially the length of the tank, an insulating slab supported on the lower face of the lug by a plurality of bolts, stationary contacts on the lower face of the slab, connecting means for the main line 25 leads extending through the slab and supporting bracket, guide slots or passages at each end of the supporting lug, a bridging contact mounted for vertical reciprocating movement, rods for supporting the bridging 30 contact passing upward through the guide slots, and means for operating said bridging contact.

3. In a high potential switch, a supporting bracket having a horizontal portion for 35 supporting the oil tank and a portion for switch-board attachment, a lug on the lower side of said support extending centrally thereof, an insulating slab on the lower face of the lug, means for supporting said slab, 40 said means being on a line in the center of the lug, one or more pairs of stationary contacts on the lower face of the slab, connecting means extending from each stationary contact out through the top of the oil tank, 45 a bridging contact for each pair of stationary contacts, supporting rods for said bridging contacts mounted for vertical reciprocating movement in guide slots in each end of the said lug, and means for operating 50 said rods comprising a suitable toggle mechanism and operating switch handle.

4. In an oil switch, an oil tank, a cover therefor, a stationary contact in said tank, a contact terminal extending upward from 55 said contact, a line terminal or conductor connected to said contact terminal, and an insulating sleeve loosely surrounding said connection and extending loosely through the tank cover, whereby said sleeve insulates 60 the connection from the cover and may be readily moved upward on the line terminal to expose the connection.

5. In a switch, an oil tank, a cover therefor, an insulating slab secured to the lower 65 side of said cover, a contact supported on

the lower side of said slab, contact terminals extending upward through the slab and tank cover, means separably connecting each contact terminal to a line terminal, an insulating sleeve loosely surrounding the connection and extending loosely through the 70 cover, whereby said sleeve insulates the connection from the tank cover and may be readily moved upward on the line terminal to expose the connection.

6. In an oil switch, an oil tank, a cover therefor, a plurality of stationary contacts within said tank, contact terminals threaded at their upper ends and extending freely through the oil tank cover, a plurality of 80 line terminals, each having a threaded portion, connecting sleeves joining the threaded portions of the contact terminals and line terminals, and an insulating bushing loosely surrounding each connection and extending 85 freely through the tank cover, whereby said sleeves insulate the connections from the tank cover and may be slipped upward at will to expose the connections.

7. In an oil switch, an oil tank, a cover 90 therefor, a stationary contact in said tank, an insulating support therefor, a connection between said stationary contact and a line terminal, said connection extending freely through the tank cover and an insulating 95 sleeve loosely surrounding said connection and passing loosely through the tank cover, whereby the connection is well insulated from the cover and said sleeve can be moved freely upward from the tank cover along 100 the line terminal so as to expose the connection.

8. In a switch, a bracket, stationary and movable contacts, contact terminals extending loosely through the bracket, line terminals, and separable means connecting the line terminals and contact terminals, insulating bushings loosely surrounding the connections and extending loosely through the bracket, whereby the connections are insulated 105 from the bracket and said bushings can be moved upward from the latter along the line terminals so as to expose the connections.

9. In a switch, a bracket, an insulating 115 supporting member secured to the lower side thereof, stationary contact members carried by said insulating supporting member, contact terminals extending upward freely through the bracket, line terminals, means 120 separably connecting the line terminals and contact terminals, and insulating sleeves loosely surrounding the connections and passing loosely through the bracket, and being supported at their lower ends below the 125 same, whereby said sleeves insulate the connections from the bracket, and can be moved upward along the line terminals at will so as to expose the connections.

10. In an oil switch, a contact, an inclo- 130

sure for said contact adapted to contain oil, a line terminal having a separable connection with the contact, an insulating sleeve loosely surrounding the connection and extending loosely through one of the walls of the inclosure whereby the connection is insulated from said wall and the sleeve may be slipped along the terminal to expose the latter.

- 10 11. In combination in a switch, a receptacle, stationary and movable contacts in said receptacle, a contact terminal extending loosely through a wall of said receptacle, a line terminal, separable means con-

necting said line terminal and contact terminal, an insulating bushing loosely surrounding the connection and extending loosely through said receptacle wall whereby the connection is insulated from said receptacle, said bushing being movable away 20 from said receptacle wall along the line terminal so as to expose the connection.

In testimony whereof I affix my signature, in the presence of two witnesses.

HERMON L. VAN VALKENBURG.
